UNITED STATES PATENT OFFICE.

ALBERT GEORGE TRIGG, OF LONDON, ENGLAND.

VARIABLE CONDENSER FOR WIRELESS TELEPHONY.

Application filed June 15, 1925, Serial No. 37,365, and in Great Britain December 16, 1924.

This invention relates to variable condensers for wireless telephony of the kind wherein movable vanes are caused to interleave with fixed vanes.

5 In condensers of this kind as ordinarily constructed the movable vanes are fixed to a rotatable spindle. In some cases the vanes secured to the rotatable spindle are offset in the plane of rotation; but such movable vanes 10 cannot be rotated independently of each other.

According to this invention the movable vanes are so constructed and arranged as to be capable of independent movement when 15 rotated in the anti-clockwise direction. In carrying out this invention each movable vane is mounted to rotate on a fixed spindle and is provided with a tooth or projection located near to the axis of rotation, the movable vanes being arranged on said axis with the teeth of each slightly in advance of the next in the series. These teeth or projections are engaged by a pin connected to a plate rotated by the adjusting handle of the 20 condenser and are carried round together in a clock-wise direction. But in the reverse action the vanes will be picked up one by one by the pin on the adjusting handle thus 25 spreading them out through the angle of rotation, in which spread out position they can be further reversely rotated if so desired.

My invention is illustrated in the accompanying drawings in which:—

35 Fig. 1 is a section taken on the line 1—1 of Fig. 2;

Fig. 2 is a plan view of the condenser with the cover removed;

Fig. 3 is a fragmentary view showing four 40 movable vanes with teeth or projections on their bosses;

Fig. 4 is a plan view of the assembled vanes in the closed position and shows the actuating pin; and

45 Fig. 5 is a plan of the assembled vanes in the opened out position.

In these drawings 1 represents the stationary vanes of the condenser secured to the casing 2 by bolts 3. Each of these vanes 50 is of an arcuate shape having a central semi-circular recess 1^a.

4 represents a fixed shaft on which are loosely mounted the movable vanes 5. Each of these vanes 5 is mainly semi-circular in plan and has a semi-circular boss 6^a, 6^b, 6^c and 6^d at its centre said bosses corresponding

to and loosely fitting in the recesses 1^a in the stationary vanes. Each boss 6^a, 6^b, 6^c and 6^d on the movable vanes 5 is provided with a tooth or notch 7^a, 7^b, 7^c and 7^d. As will 60 be seen from Fig. 3 these teeth or notches are stepped one in advance of the other with respect to the straight edge 7 of the vane.

The cover 8 of the condenser has passed therethrough a rotatable shaft 9 provided 65 with a pointer to pass over a graduated scale in the usual manner. To the bottom of the rotatable shaft 9 is secured a plate 10 carrying a pin 11. The pin 11 is parallel to the fixed shaft 9 and eccentric to the axis of said 70 shaft and extends into the casing 2 beyond the movable vanes and engages in the teeth or projections of all of them.

The condenser operates as follows:—

On rotation of the shaft 9 in the clockwise 75 direction the pin 11 presses against the straight edges 7 of all the movable vanes (4 only are shown but there may be any suitable number) and moves them all together in that direction. This is the position of the parts 80 shown in Fig. 4. By rotating the shaft 9 in the anti-clockwise direction however the movable vanes 5 will be rotated one by one until they occupy the fanned out position in Fig. 5, whereafter they may be further rotated in the anti-clockwise direction if so desired. Clockwise rotation of the vanes from the position shown in Fig. 5 will again close 85 them together as shown in Fig. 4, whereafter they may be further rotated if so desired in 90 the clockwise direction.

I claim:

1. A variable condenser for wireless telephony comprising a series of fixed vanes, a series of movable vanes rotatably mounted 95 so as to be brought into or removed from the spaces between the fixed vanes, a knob or handle for moving said vanes, the said movable vanes being so made that all of them open out or close fanwise in succession 100 by operation of the knob or handle alone.

2. A variable condenser for wireless telephony comprising a series of fixed vanes, a series of movable vanes rotatably mounted 105 so as to be brought into or removed from the spaces between the fixed vanes, a knob or handle for moving said vanes, each of the said movable vanes being mounted to rotate on the same fixed spindle, the said movable vanes being so made that all of them open 110 out or close fanwise in succession by operation of the knob or handle alone.

3. A variable condenser for wireless telephony comprising a series of fixed vanes, a series of movable vanes rotatably mounted so as to be brought into or removed from the spaces between the fixed vanes, a straight edge on each movable vane, a knob or handle for moving said vanes, each of the said movable vanes being mounted to rotate on the same fixed spindle, a tooth on each movable vane in advance of the tooth on the immediately preceding vane, and means, connected with the knob or handle, for successively engaging, by rotation in one direction, the teeth of succeeding vanes and for operating on the straight edges of all the movable vanes when rotated in the opposite direction. 30
5. A variable condenser for wireless telephony comprising a series of fixed vanes, a series of movable vanes rotatably mounted so as to be brought into or removed from the spaces between the fixed vanes, a straight edge on each movable vane, a knob or handle for moving said vanes, each of the said movable vanes being mounted to rotate on the same fixed spindle, a tooth on each movable vane in advance of the tooth on the immediately preceding vane, a rotatable shaft mounted in the condenser and to which the knob or handle is secured, a plate secured to said shaft, and a pin on said plate which on rotation of the shaft in one direction successively engages the teeth on succeeding movable vanes and on rotation in the opposite direction engages the straight edges of all the movable vanes and moves them simultaneously. 35
4. A variable condenser for wireless telephony comprising a series of fixed vanes, a series of movable vanes rotatably mounted so as to be brought into or removed from the spaces between the fixed vanes, a straight edge on each movable vane, a knob or handle for moving said vanes, each of said movable vanes being mounted to rotate on the same fixed spindle, a tooth on each movable vane in advance of the tooth on the immediately preceding vane, a rotatable shaft mounted in the condenser and to which the knob or 40
